UNITED STATES PATENT OFFICE

ALFRED E. ISCHINGER, OF PHILADELPHIA, PENNSYLVANIA

CHECK WRITER

Refiled for abandoned application Serial No. 265,219, filed December 4, 1918. This application filed March 18, 1926. Serial No. 95,814.

This application is a substitute for my abandoned application Serial No. 265,219, filed December 4, 1918.

The object of this invention is to provide 5 a new and improved machine for printing or writing checks and more especially for writing on the check the number, date, name of the payee and the amount in figures as well as words for which the check is drawn. 10 This and other objects of the invention will be illustrated in the drawings, described in the specification and pointed out in the claims at the end thereof.

In the accompanying drawings:

15 Figure 1 is a top plan view of my improved check writer.

Figure 2 illustrates a check on which the number, name, amount and date of the check have been printed as it will be done with 20 my improved device.

Figure 3 is a section on the line 3*-3* of Figure 1.

Figure 4 is a section on the line 4*-4* of Figure 3.

25 Figure 5 is a section on the line 5*-5* of Figure 1.

Figures 6, 7, 8 and 9, are plan and side elevations of washers used in connection with the printing wheel and link of my 30 invention.

Figure 10 is a crank for operating the link and printing wheel.

Figure 11 is a detail view of the shaft carrying the printing wheel, etc.

35 Figure 12 shows the link for limiting the travel of the spacing or feeding arm.

Figure 13 is a detail view of a portion of the picket or comb by which the operation of the printing lever is gaged.

40 Figure 14 is a section on the line 14*-14* of Figure 3.

Figure 15 is a section on the line 15*-15* of Figure 3.

45 In the accompanying drawings, like reference numerals indicate like parts.

For convenience, I have illustrated the invention applied to a machine such as is shown in the patent to Sampson No. 1,141,270, although it is obvious that the

invention will be applicable to other forms of check writers as well.

In the drawings, reference numeral 1 indicates the base of the check writer covered by a plate 2, above which is carried a casing 3 in which is contained the printing wheels and link and the mechanism for operating them. Mounted in the base and casing is a sleeve 4 having a shaft 5 therein. On the sleeve is fastened a segmental beveled gear 6, which meshes with the bevel gear 7, which is cast integral with the pinion 8, carried on the stud 9. The pinion 8 meshes with the pinion 10, carried on the stud 11, and this, in turn, meshes with the pinion 12, cast integral with the printing wheel 13, which printing wheel is mounted to rotate loosely on the shaft 14. This printing wheel carries words or combinations of words, made up of letters, which words are used for writing the amount of the check as appears from the line in Figure 2, reading "Fourteen thousand two hundred fifty dollars, ten cents."

The shaft 14 is cut with a flat seat that is indicated at 15. The shaft is grooved 75 with annular grooves at 18 and 19. Into the groove 18 extends a small projection of the casing shown at 18-A to prevent its moving endwise. The sides of the shaft in the groove 19 are cut flat so that the ends 80 of the lever or handle 20 can be slipped over and then pressed together, which engages therewith for the purpose of turning it.

The washers 16 and 17 are provided with the eccentric circular openings 21 and 22, 85 one side of which openings is left flat corresponding to the shape of the shaft 14 at its seat 15 so that the washers will positively engage therewith and rotate therewith. The thick washer 16 supports the printing wheel 90 23 on the shaft and the wheel 23 rotates freely on said washer. The thin washer 17 supports the end of the link 24 shown in Figures 3, 5, 12 and 14 and if rotated, moves the link back and forth. The openings 21 and 22 in the washers 16 and 17 are eccentric to the centers of the washers, and are, therefore, eccentrically placed on the shaft 14 and hold the printing wheel 23 and the end of the link 24 eccentrically thereon. 100

The washer 16 turns freely inside of the circular opening in the printing wheel 23 and does not turn it but merely raises and lowers it. The washer 17 turns freely inside the circular opening of the link 24 and moves its back and forth. The turning of the shaft 14 is secured by the handle 20, which will lock itself into engagement in the recesses 25 and 26 of the casing and will be held thereby in either up or down position. The printing wheel 13 will not be effected by the rotation of the shaft 14, but the type wheel 23 will be raised or lowered by the rotation of the shaft 14 and the link 24 will be moved endwise forward and back thereby.

When the handle 20 is in the position shown in Figures 4 and 5 as indicated at A the wheel 13 will print on the check and the wheel 23 will not print on the check.

When the handle 20 is rotated 135° from the position shown in Figure 5 to the position indicated at B, the wheel 13 will not print on the check and the wheel 23 will print on the check, and with the new position of the handle 20, the link 24 will be shifted so as to limit the operation of the variable feed mechanism and make it feed the check a uniform amount with each printing operation. The mechanism by which this result is secured will now be described.

Below the printing wheel is carried a grooved platen 30, the grooves of which correspond with the grooves of the type in both printing wheels. With each printing operation the platen is raised to press or strike the check against the type exposed in line therewith on the printing wheel. This platen is carried on the end of an arm 31 pivoted at 32. The forward end of the arm is provided with the adjusting device 33 by which the platen may be adjusted. The rear end of the lever makes contact with the shaft or pin 5, which is carried in the sleeve 4. This pin is normally held in raised position by the spring 34 which is fastened at its upper end to the casing 3 at 35 and at its lower end to a projection on the platen arm 31. On the upper end of the sleeve 4 is carried the narrow casing 40 in which is mounted a lever 38 pivoted at 39, having an anti-friction roller mounted thereon at each end. The rear end of the lever 38 engages the top of the pin 5 for the purpose of pressing it down.

On the forward end of the casing 40 are the lugs 41 between which the handle 42 is mounted to oscillate at 43. The rear end of this handle engages with an anti-friction roller on the front end of the lever 38, which in turn engages with and operates the pin 5. The lever 42, casing 40, lever 38 and sleeve 4 all swing together so that the handle 42 may be brought opposite to any of the openings in the picket 44, each of which openings represents a letter of the alphabet

as is indicated by the scale 45 in Figure 1. This scale is carried on top of the casing 3 and is stationary. A pointer 46 is carried on the casing 40 and rotates therewith, pointing to the various letters in succession. As the handle 42 is turned, the casing 40, gears 6, 7, 8 and 10 all turn therewith and this turns the type wheel 13 as well. The type wheel 23 is loosely fastened to and turns with the type wheel 13. This is secured by the slot 47 in the type wheel 23 and pin 48 in the type wheel 13, the loose connection being necessary because of the eccentricity of the wheel 23. As the wheels move together, the same lever and gearing can be used to turn both of them.

As pointed out above, when the wheel 23 is in its raised position, the platen will make contact with the wheel 13 only, and when the wheel 23 is in its low position, the platen will make contact with the wheel 23 only. The check is placed between the platen and the wheels so that the printing is secured thereon by either wheel as may be desired. I have shown one type wheel 23 eccentrically mounted on the shaft 14 but it is obvious that two or more type wheels may be mounted thereon in the same manner and each of them may be brought one at a time into operation on the shifting of the lever 20 to the correct position by setting the washers 16 therefor at different angles on the shaft 14 in assembling the machine.

The check is fed to the left in Figures 1 and 4 and toward the observer in Figure 3 and away from the observer in Figure 5. The mechanism by which the feeding is secured will now be described.

Mounted in the base is the shaft 50 having a ratchet wheel 51 thereon, which is fed by the pawl 52 carried on a crank 53 and operated by the lever 54, which lever rocks on a fixed pivot at 59. Movement is communicated to the lever 54 from the pin 4 as follows:

Fastened to the bottom of the pin 4 is the plate 61 which has a sliding engagement with the pin 62. This pin at the top has a block 63 thereon which makes pivoted connection with the lever 54 at 64. Below the plate 61 is a block 65 which slides on the pin 62 and compresses the spring 66 thereon against the head at the bottom of the pin. When the pin 4 is pressed down, it pushes the block 65 down and thru the spring 66 presses the pin 62 down as well until the lever 54 encounters resistance at the upper end, which may be encountered early or late in the movement of the pin 4, after which the lever 54 remains stationary while the pin 4 moves further to bring the platen into contact with the type to cause the printing on the check, which printing occurs at the end of the movement of the pin 4. In permitting this movement, the spring 66 is

usually compressed to a greater or less extent. The movement of the lever 54 is determined by the elevations on the mutilated end of the cylinder 55 with which it rocks into contact from its normal position. The 5 mutilations permit a travel of the lever and feed of the check proportional to the length of the word or words that are printed by line used on the printing wheel 13 with that particular operation. The words on the type 10 wheel 13 are of different lengths and different length feeds are necessary therefor. The letters and characters on the type wheel 23 are of uniform length and uniform feed is necessary when that wheel is in operation. The feed of variable length is changed to a 15 short uniform feed as follows:

When the type wheel 23 is thrown into position for printing, the link 24 is thrown to the left in Figure 3 and the end of it intercepts between the end of the lever 54 and the mutilated end of the cylinder 55 and permits the lever to move only an uniform distance equal to the distance between centers of letters. In this way an uniform feed 25 of the ratchet wheel 51 and of the feeding wheel 56 is secured. The first space at the left of the first picket in Figure 13 is partially filled in as shown at 58 to limit the 30 downward movement of the lever 42 enough to secure the feed of the check only and not enough to secure printing. This filled space in the picket is beneath the blank space of the dial and is for the purpose of spacing 35 blank between names or words as desired without printing. The link 24 is slotted at 57, thru which slot extends the shaft 11. The shaft guides the movement of the link where it passes between the casing and the 40 end of the sleeve on the pinion 10 and is thereby held steady.

In Figures 3 and 14 I have shown inking rollers 67 and 68 by which ink is supplied to the printing wheels of the machine.

45 I claim:

1. In a printing machine, the combination of a shaft, two printing wheels mounted thereon, and connections between one of said wheels and the shaft whereby on the turning 50 of the shaft the wheel is shifted radially with reference to the other wheel for the purpose of selecting the one or the other of said wheels for a printing operation.

2. In a printing machine, the combination 55 of a shaft, two printing wheels mounted thereon, connections between one of said wheels and the shaft whereby on the turning of the shaft the wheel is shifted radially with reference to the other wheel for the purpose of selecting the one or the other of said wheels for a printing operation, a platen for making contact with said wheels, and means for moving said platen and wheels relatively to each other to secure a 60 printing operation of the selected wheel.

3. In a printing machine, the combination of two parallel printing wheels mounted on a single shaft, a platen placed parallel to said shaft and movable relative to said wheels to make printing contact therewith, and means carried by said shaft and operated on the rotation thereof for moving one of said wheels radially relatively to the other wheel so as to throw part of the periphery thereof exposed to the platen out of line with the periphery of the other wheel, whereby the platen makes contact with but one or the other of said wheels. 70

4. In a printing machine, the combination of parallel printing wheels having characters thereon mounted on a single shaft, a platen placed parallel to said shaft and movable relatively to said wheels to make printing contact therewith, said shaft having an eccentric thereon on which one of said wheels is mounted, said shaft being turned independently of the wheels to change the position of the eccentric relative to the characters on said wheel, so as to throw part of the periphery thereof exposed 80 to the platen out of line with the periphery of the other wheel whereby the platen makes contact with one or the other of said wheels. 85

5. In a printing machine, the combination of two parallel printing wheels mounted on a single shaft, means for bodily shifting one of said printing wheels and causing either of said wheels to print independently of the other on paper, means for feeding the paper after printing thereon, said feeding mechanism having normally a variable throw, and means to limit its operation to cause a short, 90 uniform feed. 95

6. In a printing machine, the combination of two parallel printing wheels mounted on a single shaft, said shaft having a key way thereon, a washer eccentrically keyed on said shaft, one of said printing wheels mounted to rotate on said eccentric, and a handle on said shaft for shifting the 100 position of said shaft and the eccentric in said wheel. 105

7. In a printing machine, the combination of two parallel printing wheels mounted on a single shaft, said shaft having a key way 115 thereon, a washer eccentrically keyed on said shaft, one of said printing wheels mounted to rotate on said eccentric, and means for rotating and fastening said shaft in either of a plurality of positions to cause a printing operation by one or the other of said wheels. 120

8. In a printing machine, the combination of a shaft and two parallel printing wheels, means mounting said printing wheels directly on the shaft, eccentrically to each other, and a loose connection between said wheels which causes them to rotate together each around its own center. 125

9. In a printing machine, the combina- 130

tion of a shaft and two parallel printing wheels, means mounting said printing wheels directly on the shaft, eccentrically to each other, a loose connection between said wheels which causes them to rotate together each around its own center, and means whereby the eccentricity of the one wheel can be shifted at will.

10. In a printing machine, the combination of a shaft and parallel printing wheels mounted thereon, a feeding mechanism operating in connection with said printing wheels for feeding the paper printed thereby, said mechanism normally having a variable movement when cooperating with one printing wheel, and a link movable by said shaft to block the movement of said feeding mechanism and reduce it to an uniform amount for cooperation with the other printing wheel.

11. In a printing machine, the combination of a shaft, and eccentric on said shaft, two type wheels mounted side by side on the shaft and eccentric whereby the turning of said shaft and the eccentric without turning the wheels will cause one wheel to be shifted laterally with relation to the other wheel.

12. A printing apparatus comprising a plurality of rotary type carriers each provided with a plurality of type forms, a platen, platen operating mechanism, a single adjustable paper feeding mechanism which cooperates individually with each type carrier, means for placing one of the type carriers in printing position, means for rotating the selected type carrier to bring the type forms thereof selectively to the printing point, and operating means for effecting an impression of the selected type form and actuating said feeding mechanism.

13. A printing apparatus comprising a plurality of rotary type carriers each provided with a plurality of type forms, a platen, platen operating mechanism, a single adjustable paper feeding mechanism which cooperates individually with each type carrier, means for placing one of the type carriers in printing position and adjusting said feeding mechanism for proper cooperation with the selected type carrier, means for rotating the selected type carrier to bring the type forms thereof selectively to the printing point, and a single mechanism operating means cooperating with said platen operating mechanism, and feeding mechanism for effecting an impression of the selected type form and feeding the paper.

60 In testimony whereof I affix my signature.

ALFRED E. ISCHINGER.
